UNITED STATES PATENT OFFICE.

THOMAS J. SPENCER, OF FALLS CITY, NEBRASKA.

WINDOW-SHADE FIXTURE.

SPECIFICATION forming part of Letters Patent No. 723,748, dated March 24, 1903.

Application filed May 12, 1902. Serial No. 106,983. (No model.)

To all whom it may concern:

Be it known that I, THOMAS J. SPENCER, a citizen of the United States, residing at Falls City, in the county of Richardson and State 5 of Nebraska, have invented certain new and useful Improvements in Window-Shade Fixtures, of which the following is a specification.

My invention relates to improvements in 10 window-shade fixtures; and the object of my invention is the provision of a simple, inexpensive, and practical means for adjusting the shade with reference to the window to admit the light at the upper or lower portion 15 of the window, as desired.

To attain the desired object, my invention consists of a window-shade fixture embodying novel features of construction and combination of parts, substantially as disclosed 20 herein.

Figure 1 represents a front elevation of a window-frame provided with my fixture. Fig. 2 represents a similar view with parts of my fixture in section. Fig. 3 represents a 25 side view, and Figs. 4 and 5 represent detail views, of parts of my fixture. Fig. 6 is an enlarged detail in side elevation.

In the drawings the letter A designates the window-frame to which my fixture is applied, 30 and to one of the upper corners of the frame is attached the post, which carries the casing and drum B', in which is journaled the single grooved guide-wheel B², and formed on the casing is the tubular chain-guide B³. 35 To the opposite corner of the frame is secured the post C, carrying the drum or casing C', in which is mounted the pair of grooved guide-wheels C², and this casing is also formed with a tubular chain-guide C³.

The shade-supporting bar D carries the depending shade-brackets E, which support the shade F, and adjacent to the shade-brackets are secured the sleeves G, which are each formed with a lug H, to which lugs are connected the cord or chain J, which passes through the guide B³ over the rollers or wheels B² and C² and has its lower end connected to the inner end of the link K, and to the other lug is connected the cord or chain L, which 45 passes through the guide C³ over one of the wheels C² and has its lower end connected to the other end of the link K. From this con-

struction it will be seen that the shade is supported upon the bar and that it can be rolled and unrolled with ease and that by raising 55 or lowering the chains the shade can be adjusted with reference to the window to admit the light above or below, and to hold the shade at any adjustment I provide a novel mechanism. This consists of the post M, secured 60 to one side of the frame at the lower portion, upon which post is mounted the drum N, in which revolves the shaft O, having connected therewith the tape P, which is adapted to be wound and unwound and which passes out of 65 the drum and is connected at the upper end to the link at Q. To the outer end of the shaft O is secured the arm R, which is formed with the sleeve S, in which is fitted the horizontal bolt T, having a handle U and adapted to engage 70 any one of the openings V in the drum, and the bolt is forced into any of the openings V by means of the spring W, forming a spring-bolt. It will thus be seen that the bolt can be released and the tape wound or unwound upon the shaft and the shade adjusted, and when at the desired place the spring-bolt 75 will engage one of the openings and hold the shade at the proper place. I also provide the chain X, which is connected to the link K at 80 one end and has the other end connected to the keeper Y, and the chain serves to draw the shade up and down, and the keeper holds the chain by the engagement of the chain in the keeper.

The chain X is used for ordinary light-weight shades, and the tape with operating mechanism is used for heavy shades.

It will be seen that I provide a fixture of ornamental appearance which can be made 90 at a comparatively low price and which is efficient and practical for the purpose intended.

I claim—

1. In a window-shade fixture, the combination of the shade, the supporting-bar, the operating connections leading from the bar, the single and double guide-wheels for the connections, the link connected to the lower ends of the connections, the chain connected to the link and the keeper for holding the chain at the proper adjustment, the drum secured to the casing, the shaft in said drum, the tape adapted to be wound upon the drum, the 95 100

hook on the end of the tape to be connected to the chain, the crank on the shaft for winding the tape, and the spring-bolt carried by the crank to engage the drum to hold the tape rigid when desired.

2. In a window-shade fixture, the combination of the bar, the shade-brackets depending therefrom, the shade mounted in the brackets, the sleeves on the bar having a lug, the cords or chains connected to said lugs, the guides to receive the chains and lug, the wheels for guiding the chains, the link connected to the lower ends of the chains, the operating-chain, and the keeper for holding

the chain at the desired adjustment, the drum secured to the casing, the shaft in said drum, the tape adapted to be wound upon the drum, the hook on the end of the tape to be connected to the chain, the crank on the shaft for winding the tape, and the spring-bolt carried by the crank to engage the drum to hold the tape rigid when desired.

In testimony whereof I affix my signature in presence of two witnesses.

THOMAS J. SPENCER.
